CONTROL MECHANISM FOR NEEDLE-EYE
POLISHING MACHINES

Max O. Hoffmann, Elizabeth, N. J., assignor to
The Singer Manufacturing Company, Elizabeth,
N. J., a corporation of New Jersey

Application March 31, 1942, Serial No. 436,996

11 Claims. (Cl. 192—139)

This invention relates to machines for polishing the eyes of needles and more particularly to mechanism for bringing the machine to rest after a predetermined number of revolutions of the main shaft of the machine.

One of the objects of this invention is to increase the range of usefulness of the ratchet and pawl stop-motion mechanism now in use on needle-eye polishing machines.

Another object is to provide a self-contained attachment which may be applied to existing machines with the minimum of effort and expense.

A still further object of this invention is to provide an attachment for application to a needle-eye polishing machine in which a predetermined number of operations or cycles of the machine may be readily selected.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

While the invention in its broadest aspects is capable of embodiment in numerous forms, a preferred embodiment thereof is illustrated in the accompanying drawings, in which—

Fig. 1 is a top plan view of a portion of the frame of a needle-eye polishing machine showing my improved control mechanism embodied therein.

Fig. 2 is a side elevation, partly in section, of the mechanism shown in Fig. 1.

Fig. 3 is a vertical section taken along the line 3—3 of Fig. 1.

Fig. 4 is a vertical section taken along the line 4—4 of Fig. 1.

Fig. 5 is a horizontal section taken along the line 5—5 of Fig. 3.

Fig. 6 is a side elevation of the ratchet and pawl mechanism.

Fig. 7 is a side elevation of the selective control mechanism and the belt shifting mechanism which it controls.

In the embodiment illustrated, 1 represents a countershaft journaled in the bearing brackets 1' and carrying belt pulleys 2 and 3 (Fig. 7). The pulley 2 is fixed to the shaft 1, and the pulley 3 is loose and adapted to rotate thereon and these pulleys are adapted to be rotated by a belt 4 which may be driven from any suitable

source of power. The belt 4 may be shifted from the loose pulley 3 to the driving pulley 4 by a belt shifter comprising a rod 5 mounted from sliding movement in the lugs 5^a and 5^b, formed on the brackets 1'. The rod 5 is provided at one end with the arms 6 which embrace the belt 4, and at its other end with a groove pulley 7, there being a tension spring 8 having one end secured to the rod 5 and its other end secured to the lug 5^b which tends to slide the rod 5 to the right as viewed in Fig. 7 and thus shift the belt from the driving pulley 2 to the loose pulley 3.

A portion of the frame of a needle-eye polishing machine similar to that shown in the patent to Beers, No. 407,324, dated July 23, 1889, is indicated at 10 and journaled in bearings 11 and 12, carried by the frame is a main driving shaft 13 having a driving pulley 14 fixed to one of its ends and a crank arm 15 fixed to its other end. The pulley 14 is driven by means of a belt 16 from the pulley 9 fixed to an overhead shaft 1.

The crank arm 15 actuates a connecting rod 15' which is connected to and adapted to reciprocate the needle-clamp carriage on the frame of the machine. Fixed to the shaft 13 is an eccentric 17 which is embraced by one end of a pitman 18, the other end of the pitman being pivotally connected at 18' to a rock-arm 19 having a hub 20 journaled for oscillatory motion on a shaft 21 which is rotatably carried by the bearings 22 and 23, fixed to the frame 10 of the needle-eye polishing machine.

Fixed to the shaft 21 are three ratchet wheels 24, 25 and 26 formed with different numbers of teeth on their outer periphery. Cooperating with the teeth are pawls 27, 28 and 29 fixed to and carried by the rock-arm 19 by means of a pivot screw 30. It will be obvious that when the machine is operating only one of the pawls 27, 28 or 29 is selected to be in operative position to advance the shaft 21 step-by-step. In Fig. 1 pawl 27 is shown as the effective pawl used to advance the ratchet wheel 24 and the other two pawls 28 and 29 have been placed in their inoperative positions. As shown in Fig. 6 the pivotal connection 18', between one end of the pitman 18 and the lever 19, may be shifted along the lever 19 towards and from the axis about which it oscillates to vary the throw imparted to the pawls, and thereby cause the pawls to advance the ratchet wheel with which it cooperates one or more teeth for each oscillation of the lever 19. To adjust the pivotal point 18' the set screw 35 is loosened and the C-shaped mem-

ber 36, which embraces the arm 19, is slid along the arm to the desired position at which point the set screw 35 is tightened to hold the C-shaped member in the selected position.

In order to prevent retrograde movement of the ratchet wheels 24, 25 and 26, locking pawls 37 are provided. These pawls are pivotally carried on an arm 38 fixed to the frame of the machine. To prevent overthrow of the shaft 21, a drum 39 is fixed to the shaft and a belt 40 having one of its ends fixed to the frame of the machine, and a weight 41 secured to its other end is wrapped around the drum 39 so as to act as a frictional brake.

Adjustably fixed to the frame 10 of the machine by the screws 42 is a bracket 43 having upstanding ears 44 and 45 which carry a short shaft 46. Located between the ears 44, 45 and fixed to the shaft 46 is a lever 47 having two arms 48 and 49. The arm 48 is provided with a series of holes 50 which are adapted to be selectively aligned with a shouldered plunger 51 carried by the arm 44 and urged towards the lever by a spring 52. The plunger 51 is adapted to be moved back against the action of the spring by means of a knob 53 fixed to the reduced end of the plunger. Carried by the arm 49 of the lever 47 is an adjustable stop screw 54 which is adapted to be locked in adjusted position by a lock-nut 55.

Carried by the shaft 46, for swinging movement thereon, is a hub 57 formed with a laterally extending weighted portion 58 to which a toothed segment 59 and a controlling member 60 are secured by the screw 61 and the pins 62 and 63. Cooperating with the controlling member 60, the outer periphery of which has the shape of a segment of a circle, is a brake-shoe 64 which has a bearing face complementary to the outer periphery of the member 60.

The brake-shoe 64 is adjustably secured by the screw 65 to the upstanding leg 66 of a bell-crank lever 67. The bell-crank lever 67 is pivotally secured between a lug 68 formed on the bracket 43 and the upstanding ear 45 by means of a pivot pin 69. The free end of the arm 70 is connected to a chain 71 which rides over the grooved pulley 7 and has one of its ends secured to the lug 5a. The chain may extend through a suitable opening in the frame 10, over the grooved pulley 72 and forward to the front of the machine where it may be connected to any suitable actuating mechanism. Cooperating with the ratchet segment 59 is a finger 73 formed on a hub 74 fixed to the shaft 21 by a screw 75. It will be understood that each time the shaft 21 makes one complete rotation the finger 73 engages one of the teeth of the ratchet segment and advances or moves the ratchet segment 59 the distance of one tooth about the shaft 46 as a pivot.

Operation

Assuming that the necessary number of strokes of the polishing thread through the eye of the needle that is to be placed in the machine has been determined and the pawl 27 has been placed in operative position, the pawls 28 and 29 remaining in inoperative position, and the pivotal point 18' of the pitman 18 adjusted so that the pawl 27 will advance the ratchet wheel 24 a certain number of teeth. Assuming further that the pin 51 has been inserted in the hole b of the member 48 and the lever 67, brake-shoe 64 and control member 60 are in the position indicated in Fig. 7.

To start the needle-eye polishing machine the

operator first pulls on the chain 71 or pushes down on the arm 70 of the bell-crank lever 67 until the lever 67 reaches its lowest position at which point it will engage the lower part of the bracket 43. When the lever is in this position the shoe 64, carried by the arm 66 of the bell-crank lever, will have moved from under and thus release the control member 60 which, due to the weighted part 58, the hub 57, ratchet segment 59 and the control member 60 will fall downwardly about the shaft 46 as a pivot until the lower part of the pawl segment 59 engages the adjustable stop-screw 54. When the parts are in this position the control member 60 is back of the shoe 64 and when the lever 67 or chain 71 is released by the operator it is held in the position shown in Figs. 2 and 3, and dotted line position, Fig. 7, by the control member 60.

The downward movement of the arm 70 of the bell-crank lever 67 causes the chain 71 to shift the spring biased belt shifting lever 5 to the left, as viewed in Fig. 7, so as to cause the belt 4 to be shifted from the loose pulley 3 to the driving pulley 2 and rotate the shaft 1, pulley 9 and the pulley 14, thus starting the machine. For each rotation of the pulley 14, and its shaft 13, the pitman 18 is reciprocated and through the pawl 27 this reciprocatory motion imparts a step-by-step motion to the shaft 21. When the shaft 21 nears the end of its first complete rotation the tooth or finger 73 will engage the tooth of the segment 59 as shown in Fig. 4, and as rotation of the shaft 21 continues it moves the segment 59 upwardly the distance of one tooth about the shaft 46 as an axis. There is an upward pull on the chain 71, due to the fact that the spring 8 is attempting to shift the belt 4 to the loose pulley and, therefore, there is friction between the mating surfaces of the shoe 64 and the control member 60, and this friction holds the hub 57, ratchet 59 and control member 60 in the position to which they are moved by the finger 73. Near the end of the second revolution of the shaft 21 the finger 73 engages the last tooth on the segment 59 and at the completion of the rotation the segment is moved about the shaft 46 as an axis sufficiently far so that the control member 60 moves upwardly out of contact with the shoe 64 thereby releasing the lever 67 and permitting the spring 8 to move the belt-shifting rod 5 to the right, as viewed in Fig. 7, thereby shifting the belt 4 to the loose pulley and thus stopping the machine.

From the above it will be obvious that once it has been determined the correct number of strokes of the polishing thread through the needle-eye that are necessary in order to give the requisite amount of polish to the needle-eye, this number may be set in the control mechanism. To set in the number the correct one of the pawls 27, 28 or 29 is selected to be placed in its operative position, the other two pawls being placed in their inoperative position. The pivotal point 18' of the pitman 18 is then shifted so as to cause the operative pawl to advance the ratchet wheel one or more teeth. If it is possible to select the correct predetermined number by means of the pawl selection and the adjustment of the pivotal point 18' then the top hole a in the member 48 is selected so that after one revolution of the shaft 21 the machine will come to rest. If however it is possible to select only one-half the predetermined number by the pawl selection and adjustment of the pivotal point 18' then the next hole b is selected. If only one-third or one-fourth

of the predetermined number may be set in by the correct pawl selection and adjustment of the pivotal point 18', then the holes c and d, respectively, are selected. In other words, each number which may be selected by means of the pawls 21, 28 and 29 and the adjustment of the pivotal point 18' may be multiplied by 1, 2, 3 or 4 depending upon the position of the pin 51 in the holes a, b, c, d. In short, the range of usefulness of the ratchet and pawl stop-motion mechanism is increased 300% by use of the selective mechanism above described.

It will also be obvious that the auxiliary shaft 21 is always stopped in substantially the same position and therefore the controlling cam 78 on the shaft 21 which, through the link 79 controls the relative position of the needle eye to the polishing thread, also is stopped each time in the same position. Further it is apparent that a segment having more teeth than the segment 59 may be used, thereby further increasing the range of usefulness of the ratchet and pawl mechanism.

From the foregoing description considered in connection with the accompanying drawings, the construction, manner of operation and several advantages of my improved control device will be clearly and fully understood. It is apparent that such a device has a wide variety of uses, and it will be understood that the form, construction and arrangement of the several elements employed may be varied. Therefore, the privilege is reserved of resorting to all such legitimate changes therein as may be fairly embodied within the spirit and scope of the appended claims.

Having thus set forth the nature of the invention, what I claim herein is:

1. In a needle-eye polishing machine, a main shaft, means for rotating said shaft, an auxiliary shaft spaced from said main shaft, mechanism actuated by said main shaft for imparting a step-by-step rotary motion to said auxiliary shaft, means for adjusting said mechanism for varying the number of steps required to impart a complete rotation to said auxiliary shaft, and selective means for stopping said machine after a predetermined number of complete rotations of said auxiliary shaft.

2. A needle-eye polishing machine having in combination, a main driving shaft, power actuated mechanism for rotating said shaft, an auxiliary shaft, a plurality of ratchet and pawl mechanisms connecting said shafts, means for selecting one of said ratchet and pawl mechanisms to impart a step-by-step rotary motion to said auxiliary shaft and adjustable means under control of said auxiliary shaft for rendering the power actuating mechanism ineffective to rotate the main driving shaft after a predetermined number of complete rotations of the auxiliary shaft.

3. A needle-eye polishing machine, having in combination, a main driving shaft, power driven means for rotating said shaft, an auxiliary shaft, a pitman actuated by said shaft, a plurality of pawls actuated by said pitman, ratchet wheels with which said pawls cooperate and fixed to said auxiliary shaft, means for selecting one of said pawls whereby one of said ratchet wheels and said shaft may be given a step-by-step rotary motion and means for rendering said driving means ineffective to rotate the main shaft after a predetermined number of rotations of the auxiliary shaft.

4. A needle-eye polishing machine having in combination, a main driving shaft, power driven

means for rotating said shaft, an auxiliary shaft, a pitman actuated by said main shaft, a plurality of pawls actuated by said pitman, ratchet wheels with which said pawls cooperate and fixed to said auxiliary shaft, means for selecting one of said pawls whereby one of said ratchet wheels and said shaft may be given a step-by-step rotary motion, adjustable mean for varying the throw of said pawls and means for rendering said driving means ineffective to rotate the main shaft after a predetermined number of complete rotations of said auxiliary shaft.

5. In a needle-eye polishing machine a rotary main shaft, actuating means for said shaft, an auxiliary shaft, means for operatively connecting said main shaft and auxiliary shaft for imparting a partial rotation to the auxiliary shaft for each rotation of the main shaft, a bracket carried by said machine, a ratchet element carried by said bracket, a member actuated by said ratchet, a pivoted arm under control of said member, means operatively connecting said arm with the actuating means for the main shaft of the machine, and a pawl carried by said auxiliary shaft for imparting a step-by-step movement to said ratchet element.

6. In a needle-eye polishing machine a rotary main shaft, actuating means for said shaft, an auxiliary shaft, means for operatively connecting said main shaft and auxiliary shaft for imparting a partial rotation to the auxiliary shaft for each rotation of the main shaft, a bracket carried by said machine, a ratchet element carried by said bracket, a finger carried by the auxiliary shaft for actuating said ratchet once for each rotation of the auxiliary shaft, a member carried by said ratchet, and means under control of said member for rendering the actuating means for the main shaft of the machine ineffective to rotate the main shaft.

7. A control mechanism for needle-eye polishing machines having a main shaft, comprising, an auxiliary shaft, mechanism operatively connecting said main and auxiliary shafts for rotating the auxiliary shaft once for a predetermined number of rotations of the main shaft, selective means for varying the number of rotations of the main shaft required to give a complete rotation to the auxiliary shaft, means for bringing said machine to rest after a predetermined number of complete rotations of the auxiliary shaft, and means for adjusting said last named means.

8. A control mechanism for needle-eye polishing machines having a main shaft, comprising, an auxiliary shaft, mechanism operatively connecting said main and auxiliary shafts for rotating the auxiliary shaft once for a predetermined number of rotations of the main shaft, selective means for varying the number of rotations of the main shaft required to give a complete rotation to the auxiliary shaft, and means for stopping the rotation of the main shaft after a predetermined number of rotations of the auxiliary shaft, said last named means including a ratchet mechanism actuated once for each rotation of the auxiliary shaft, a lever pivoted to the machine, and a member actuated by the ratchet mechanism for controlling said lever.

9. A control mechanism for needle-eye polishing machines having a main shaft, comprising, an auxiliary shaft, mechanism operatively connecting said main and auxiliary shafts for rotating the auxiliary shaft once for a predetermined number of rotations of the main shaft, selective means for varying the number of rotations of

the main shaft required to give a complete rotation to the auxiliary shaft, means for stopping the rotation of the main shaft after a predetermined number of rotations of the auxiliary shaft, said last named means including a ratchet mechanism actuated once for each rotation of the auxiliary shaft, a lever pivoted to the machine, a member actuated by the ratchet mechanism for controlling said lever, and means for adjusting the initial position of the ratchet mechanism at the beginning of the cycle of operation of the machine.

10. A control mechanism for needle-eye polishing machines having a main shaft, comprising, an auxiliary shaft, mechanism operatively connecting said main and auxiliary shafts for rotating the auxiliary shaft once for a predetermined number of complete rotations of the main shaft, and means for stopping the rotation of the main shaft of the needle-eye polishing machine, said last named means including a bracket carried by the machine, a ratchet member having a plurality of teeth and carried by said bracket, a control member also carried by said bracket and movable with said ratchet member, a lever pivoted to said bracket and having one of its ends cooperating with said control member, and a fin-

ger secured on said auxiliary shaft for imparting a step by step movement to said ratchet member for each complete rotation of said auxiliary shaft.

11. A control mechanism for needle-eye polishing machines having a main shaft, comprising, an auxiliary shaft, mechanism operatively connecting said main and auxiliary shafts for rotating the auxiliary shaft once for a predetermined number of complete rotations of the main shaft, 10 and means for stopping the rotation of the main shaft of the needle-eye polishing machine, said last named means including a bracket fixed to the machine and having two upstanding ears, a ratchet segment pivotally secured between the ears of said bracket, a control member connected to said ratchet segment and movable therewith, a pivoted lever having one of its ends cooperating with said control member, a finger carried by said auxiliary shaft for actuating said ratchet segment one step for each rotation of the auxiliary shaft, and means for adjusting the position of the ratchet segment at the beginning of the cycle of operation of the machine for the purpose of predetermining the number of complete rotations the auxiliary shaft will make before rotation of the main shaft is stopped.

MAX O. HOFFMAN.
